UNITED STATES PATENT OFFICE.

CHARLES H. WILLIS, OF TIFTON, GEORGIA.

LOCOMOTIVE ASH-PAN.

1,016,464.

Specification of Letters Patent.

Patented Feb. 6, 1912.

Application filed July 5, 1911. Serial No. 636,843.

To all whom it may concern:

Be it known that I, CHARLES H. WILLIS, a citizen of the United States, residing at Tifton, in the county of Tift and State of Georgia, have invented certain new and useful Improvements in Locomotive Ash-Pans, of which the following is a specification, reference being had to the accompanying drawings.

10 This invention relates to certain new and useful improvements in locomotive ash pans and has for its primary object the provision of a comparatively simple, durable and efficient device of this character adapted to be 15 actuated by the fireman whereby the ash pan may be conveniently emptied.

Another object of the invention is to provide means arranged upon the movable bottom of the pan to prevent the same from 20 adhering to the side wall of the pan through the accumulation of wet ashes between said wall and the bottom plate, thereby facilitating the operation of the device.

Still another object of the invention is to 25 provide a frame rod having side and end walls arranged thereon and inwardly and downwardly inclined, a bottom plate pivotally mounted upon said frame, one of the longitudinal edges of the plate extending 30 beyond one of said side walls, means for limiting the movement of the bottom plate, and an operating rod attached to said plate to actuate the same.

With the above and other objects in view, 35 the invention consists of the novel features of construction, combination and arrangement of parts hereinafter fully described and claimed, and illustrated in the accompanying drawings, in which—

40 Figure 1 is a longitudinal section of a locomotive ash pan embodying my improvements; Fig. 2 is a section taken on the line 2—2 of Fig. 1; Fig. 3 is a top plan view of the pan; and Fig. 4 is a detail perspective 45 view of the movable dumping plate.

Referring in detail to the drawings 5 designates a frame preferably rectangular in form and constructed from a continuous iron rod or bar. Upon this frame rod the 50 end and side walls 6 and 7 respectively, of the pan, are erected. These walls are formed from sheet metal plates and have their lower edges bent around and closely engaged upon the frame rod as indicated at 8. The 55 contiguous ends of the side and end walls of the pan are suitably connected and rigidly se-

cured together. An operating rod 9 extends centrally beneath the frame and is supported upon the ends thereof for rotative movement in suitable bearings 10, said rod having a 60 nut 11 threaded on one end to retain the same in said bearings. To this rod 9 the bottom plate 12 is attached by means of suitable clips 13 which are of U-shaped form, the ends of said clips being disposed through 65 the plate and having nuts 14 threaded upon their extremities, said nuts engaging the under side of the bottom plate and rigidly securing the same upon the rod 9. It will be observed from reference to Fig. 4 of the 70 drawings that the rod 9 is not arranged centrally upon the bottom plate 12 between the longitudinal edges thereof, so that said plate at one side projects beyond the longitudinal bar of the frame 5 of the pan, said bottom plate at its other edge being disposed within 75 the opposite parallel portions of said frame. The rod 9 is vertically disposed at one end of the bottom plate as indicated at 9' and extended to a point adjacent the fireman's 80 seat where it is connected to an actuating lever 15 which is suitably mounted and carries a spring controlled dog for engagement with the teeth of a rack 16 arranged adjacent said lever.

The ash pan is longitudinally arranged beneath the fire box of the locomotive in the usual manner, by means of brackets or other suitable supports, and the ashes fall therefrom upon the sides and ends of said pan 90 which are inclined to direct the same upon the bottom plate thereof. Water is usually discharged upon the ashes and the same become thoroughly soaked and form a compact mass in the pan.

In order to obviate liability of the projecting longitudinal edge of the pan sticking to the lower edge of the side wall which is arranged upon the main frame 5, I provide a small wire rod 18 which is secured upon the 100 upper surface of the pan bottom and contacts with the lower edge of the side wall, to space the bottom plate therefrom. This will admit a strong draft of air at one end of the plate between the same and the frame so 105 as to dry out the ashes, and permit of the easy tilting movement of the bottom plate so that the ashes will slide therefrom.

To the inner face of one of the end walls of the ash pan and upon one side of the rod 9 110 above that portion of the bottom plate which is disposed within the walls of the pan, a

short rod 19 is secured. This rod limits the tilting movement of the bottom plate and prevents the same from assuming a vertical position under the weight of the ashes as 5 they move off of the plate.

From the foregoing it is thought that the construction and manner of operation of my improved ash pan will be fully understood.

The device is simple, durable in construction, and eliminates many of the deficiencies 10 found in devices of this character as previously constructed. The particular feature, however, resides in the provision of the longitudinally extending rod 18 arranged at 15 one edge of the bottom plate so as to space said plate and allow of the free admission of air to the body of ashes. The advantage of such construction is obvious and materially increases the ease with which the pan may 20 be emptied, and its efficiency in practical use.

While I have shown and described the preferred form and construction of the various parts, it will be understood that the invention 25 is susceptible of many minor modifications without departing from the essential feature or sacrificing any of the advantages thereof.

Having thus described the invention what is claimed is:—

30 1. A locomotive ash pan comprising end and side walls, a bottom plate pivotally mounted on said end walls for transverse tilting movement, the end and side edges of said bottom plate on one side of its pivot 35 closely engaging with the adjacent lower edges of the walls of the pan, the longitudinal edge portion of said plate on the opposite side of its pivot extending beneath and beyond the lower edge of the adjacent side wall of the pan, and means carried by said 40 plate and engaging the lower edge of said wall whereby the bottom plate on one side

of its pivot is spaced at its ends from the end walls of the pan to provide openings at the ends of the pan and permit of a free ingress 45 of air thereto.

2. A locomotive ash pan comprising side and end walls, a bottom plate mounted upon the end walls for transverse tilting movement, operating means therefor, one of the 50 longitudinal edges of said plate extending beyond the side wall of the frame, and a longitudinal rod secured upon the upper surface of said plate and engaging with the lower edge of said side wall to space said 55 plate on one side of its center and at its ends from the end walls of the frame, whereby air inlet openings are provided at the ends of the pan.

3. A locomotive ash pan comprising inclined side and end walls, a bottom plate mounted upon the end walls for transverse tilting movement, operating means therefor including a rod longitudinally arranged upon and secured to the bottom plate, one of the longitudinal edges of said plate being disposed within the opposed side wall of the frame, the other longitudinal edge of the bottom plate extending beyond the opposite side wall, means carried by said plate to 70 maintain the ends thereof, on one side of its center, in spaced relation to the end walls of the pan when the plate is in its closed position whereby air inlet openings are provided at the ends of the pan, and means secured upon one of said side walls to limit the opening movement of the pan.

In testimony whereof I hereunto affix my signature in the presence of two witnesses.

CHARLES H. WILLIS.
